Attorney

UNITED STATES PATENT OFFICE.

THOMAS J. KEHOE, OF TOLEDO, OHIO, ASSIGNOR TO THE WILLYS-OVERLAND COMPANY, OF TOLEDO, OHIO, A CORPORATION OF OHIO.

SECURING DEVICE FOR REMOVABLE PILLARS.

1,379,826.

Specification of Letters Patent.

Patented May 31, 1921.

Application filed August 8, 1917. Serial No. 185,119.

To all whom it may concern:

Be it known that I, THOMAS J. KEHOE, a citizen of the United States, residing at Toledo, in the county of Lucas and State of 5 Ohio, have invented certain new and useful Improvements in Securing Devices for Removable Pillars, of which I declare the following to be a full, clear, and exact description.

10 This invention relates to improvements in connecting and securing devices for removable pillars.

The principal object of this invention is to provide improved securing devices by 15 means of which the removable pillars, used in a convertible touring sedan body, may be secured at top and bottom to the top and body of the vehicle respectively.

Further objects, and objects relating to 20 economies of manufacture and details of construction, will definitely appear from the detailed description to follow.

I accomplish the objects of my invention by the devices and means described in the 25 following specification. My invention is clearly defined and pointed out in the appended claims.

A structure constituting a preferred embodiment of my invention is illustrated in 30 the accompanying drawings, forming a part of this specification, in which—

Figure I is a view in side elevation of a vehicle body embodying my invention.

Fig. II is an enlarged, fragmentary, sectional view, taken substantially on the line 35 II—II of Fig. I.

Fig. III is a detail view, in side elevation, showing the connection between one end of the pillar and the vehicle.

40 Fig. IV is a fragmentary, detail, sectional view, taken substantially on the line IV—IV of Fig. III, and

Fig. V is a fragmentary, detail, perspective view, showing the plate secured to the 45 end of the pillar.

In the drawings, similar reference numerals refer to similar parts throughout the several views, and the sectional views are taken looking in the direction of the little arrows 50 at the ends of the section lines.

Considering the numbered parts of the drawing, the vehicle is provided with the body 10, the permanent top 11, and the removable pillars 12, which are secured at 55 their ends to the top and body respectively,

and serve as guides for the windows. When it is desired to convert the vehicle from a closed to an open car, the windows are dropped into pockets in the side of the body, and the pillars may be removed by releasing 60 the devices connecting the pillars to the top and body, which devices form the subject-matter of my invention.

Angle plates 13 are secured to the top and the body respectively, in line with the ends 65 of the pillar, and have a block 14 secured to the horizontal portion thereof, and provided with threaded socket 15, which is inclined at an angle to the angle plate. The block 14 is housed in a recess 16 formed in 70 the part to which the angle plate is attached. Notches 17 are cut away from the angle plate 13 at the corners thereof, as shown in Fig. IV. The pillar 12 has secured to each end thereof an angle plate 18, said angle 75 plate being provided, in the horizontal portion thereof, with an inwardly-struck V-shaped groove 20, through one wall of which an opening 21 is formed. Tongues 19 are struck up from the corner of the angle 80 plate and are adapted to engage in the notches 17, formed in the corner of the angle plate 13. An opening 22 is provided in the vertical portion of the angle plate 18, and a passage 23 is formed in the end of the 85 pillar at an angle thereto, said passage having an enlarged chamber 31 near the end of the pillar. A bolt 24 is provided with a threaded end 25, which is adapted to be screwed into the socket 15, formed in the 90 block 14, said bolt being provided with a cylindrical part 26, having a bearing in the opening 21 provided in the horizontal part of the angle plate 18, and a collar 27 engaging the face of said angle plate, as shown 95 in Fig. II, and limiting the inward movement of said bolt, and adapted to engage the bottom of chamber 31 to limit the movement of the bolt in the other direction. The bolt is provided with a squared head 28, which 100 is adapted to be engaged by the squared socket 30, provided in the shank 29 of an operating wrench, by means of which the bolt can be turned.

From the description of the parts given 105 above, the operation of my device should be very readily understood. In Fig. II, the pillar 12 is shown locked in position. In order to release and remove the pillar, the wrench is applied with the squared head 28 110

- of the bolt fitting in the socket 30 of the wrench, and the bolt is rotated so as to unscrew the threaded part 25 thereof from the threaded socket 15 in the block 14. The 5 bolt is unscrewed until the end thereof is withdrawn into the groove 20, and this process is repeated at each end of the pillar. The pillar can then be removed by a straight, lateral movement.
- 10 When it is desired to secure the pillar in place, the pillar is moved to position laterally until the upstanding lugs 19, engage in the notches 17, of the angle plates 13, on top and body respectively, and limit the 15 lateral movement of the pillar and indicate that it is positioned. The bolts 24 are then screwed into the sockets in the blocks 14, thus drawing and securing the pillar in position.
- 20 I am aware that the particular embodiment of my invention, which I have here shown and described, is susceptible of considerable variation without departing from the spirit of my invention. I have found, 25 however, that this embodiment is desirable from many standpoints, and, therefore, I desire to claim the same specifically as well as broadly, as indicated by the appended claims.
- 30 Having thus described my invention, what I claim as new and desire to secure by Letters Patent is:
1. In a vehicle body provided with a body portion and a top portion, the combination therewith of a demountable pillar, and means for detachably securing one end of said pillar to one of said portions, comprising a plate carried by said portion and provided with a threaded socket, an angle plate carried by said pillar and provided with an opening through one leg thereof, and a bolt rotatably and slidably mounted in said opening and in an inclined passage in said pillar and provided with a threaded end adapted to be screwed into said socket and a collar adapted to limit the movement of said bolt in one direction by engagement with said 40 inclined portion.
  2. In a vehicle body provided with a body portion and a top portion, the combination therewith of a demountable pillar, and means for detachably securing one end of said pillar to one of said portions, comprising a plate carried by said portion and provided with a threaded socket and a recess, a plate carried by said pillar and provided with an upstanding lug adapted to seat in 45 said recess to prevent movement of said pillar outwardly or laterally, said plate being provided with an opening, and a bolt located in said opening and in a passage in said pillar and having a threaded end adapted to be screwed into said socket,

3. In a vehicle body provided with a body portion and a top portion, the combination therewith of a demountable pillar, and means for detachably securing one end of said pillar to one of said portions, comprising a plate carried by said portion and provided with a threaded socket and a recess, an angle plate carried by said pillar and provided with an upstanding lug adapted to seat in said recess to prevent movement of said pillar outwardly or laterally, said angle plate being provided with an opening through one leg thereof, and a bolt mounted to turn in said opening and in an inclined passage in said pillar and provided with a threaded end adapted to be screwed into said socket, an opening being provided in the other leg of said angle plate through which access may be had to said bolt to rotate the same.

4. In a vehicle body provided with a body portion and a top portion, the combination therewith of a demountable pillar, and means for detachably securing one end of said pillar to one of said portions, comprising a plate carried by said portion and provided with an inclined threaded socket and a recess, a plate carried by said pillar and provided with an upstanding lug adapted to seat in said recess to prevent movement of said pillar outwardly or laterally, said plate being provided with an inclined portion having an opening therethrough, and a bolt rotatably and slidably mounted in said opening and in an inclined passage in said pillar and having a threaded end adapted to be screwed into said socket and a collar adapted to limit the movement of said bolt in one direction by engagement with said inclined portion.

5. In a vehicle body provided with a body portion and a top portion, the combination therewith of a demountable pillar, and means for detachably securing one end of said pillar to one of said portions, comprising a member carried by said portion and provided with an inclined threaded socket, a plate carried by said pillar and provided with an inclined portion having an opening therethrough, a bolt rotatably and slidably mounted in said opening and in an inclined passage in said pillar and having a threaded end adapted to be screwed into said socket, said passage having an enlarged portion whereby a shoulder is formed between said enlarged portion and said passage proper, and a collar on said bolt adapted to limit movement of said bolt in opposite directions by engagement with said inclined portion and shoulder respectively.

6. In a device of the class described, the combination of a vehicle body provided with a threaded socket, a removable pillar, a bolt mounted in one end portion thereof and having a threaded end adapted to engage

said threaded socket, and a lug carried by the end of the pillar in which the bolt is mounted and engaging means on the body when the pillar is in operative position to prevent lateral movement of the pillar relative to the body either outwardly or in a direction parallel to the face of the body.

7. In a device of the class described, the combination of a vehicle body, a vehicle top, a removable pillar arranged substantially vertical between said body and top, and means to secure said pillar in tensioned position between said body and top including an inclined threaded socket in said body and

top, respectively, and a bolt located at either 15 end of said pillar and having threaded ends adapted to engage said sockets to draw said pillar at either end thereof into engagement with said body and top, said bolts being operable from inside the vehicle and 20 when released from said sockets permitting the pillar to be removed by a straight lateral movement thereof relative to the body and top while maintaining the pillar substantially vertical.

25 In testimony whereof I affix my signature.

THOMAS J. KEHOE.
